UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF DELAWARE.

BAG FASTENER.

Application filed December 11, 1922. Serial No. 606,097.

To all whom it may concern:

Be it known that I, FRANZ A. FULLER, a citizen of the United States, residing at Newark, in the county of Essex and State of New Jersey, have invented certain new and useful Improvements in Bag Fasteners, of which the following is a specification.

This invention relates to improvements in fastening devices for bags, using the term 10 in its generic sense, whereby the same is prevented from opening until the locking means are released.

One of the objects of the invention is to provide a fastener of wider utility and more 15 general adaptability than is usual.

Another purpose is to produce a fastener of exceptional simplicity and fewness of parts and these parts integrally inter-connected without solder, rivets, screws, or like 20 securing devices.

A further aim is in the provision of a neat appearing, compact and strong fastener, easy to apply and convenient to operate.

These and similar aims, objects and purposes are accomplished by the novel design, 25 construction and arrangement of parts hereinafter described and shown in the accompanying drawing, constituting an essential part of the disclosure, and in which:—

30 Figure 1 is a front elevational view showing a fragment of bag and illustrating the application of the invention thereto.

Figure 2 is a collective view in perspective of the several parts of the fastener prior to 35 assemblage.

Figure 3 is a transverse sectional view of the fastener as assembled.

Figure 4 is a perspective view of the keeper member in detail.

40 Figure 5 is a transverse sectional view of the same showing the manner in which it is attached.

Figure 6 is a similar view of the same as fully engaged.

45 In Figure 1 of the drawing a container of the bag, purse or portfolio type is indicated, the body or main portion being designated by the numeral 10 and the flap or cover portion by 11.

50 The fastener, shown attached to the portion 10, consists of a hollow rectangular casing having a level top or escutcheon plate 12 from which depends a circumjacent flange 13 flaring slightly outward at both sides and

ends, the edges of the flange resting directly 55 upon the fabric of the container.

Within this casing is a plate 14 having upturned front and rear flanges 15 suited to engage within the corresponding sides of the casing, the edges of the flanges being 60 seated against the under side of the plate 12.

Similar raised flanges 16 are provided at the ends of the plate 14, the same having lateral outstanding wings 17 parallel with the plate 14 and level with the edges of the front 65 and rear flanges.

Midway in the length of the wings 17 are continuing extensions 18 having downturned flanges 19 spaced to closely fit tightly within the end flanges 13 of the casing. 70

When so fitted the elements 19 are held in position by folding lugs 20, formed integral with the end flanges 13, of the casing, over the edges and inner sides of these elements, clamping the plate 14 rigidly to the casing. 75

It is to be noted that the height of the elements 19 is such that when the lugs 20, which are nicked as at 21, are folded over them, a level lower surface is produced.

Formed with the wings 17 at their outer 80 edges, on each side of the central projections 18, are downturned clip elements 22 suited to pass through the material of the container and be clinched on its opposite side in a manner well understood, thereby 85 securing the fastener structure firmly in place.

Movable in the space 23 between the plates 12 and 14 is a detent slide 24 its side edges being guided by lugs 25 formed from the 90 plate 14 by shearing and bending the same upward as shown.

Similar lugs 26 formed in like manner extend longitudinally to act as stops for the slide, the rear of which is reduced in thickness forming a neck 27 leading to an integral raised circular hollow head 28.

Said neck 27 projects out through an opening 29 in the plate 12, covered by the head, into the lower open part of which extends a forwardly extending prong 30 connected by the riser 31 with the plate 12, the prong and riser being formed from the material sheared in producing the opening 29. 100

Inside the head or knob 28 is a compression spring 32, one end encircling the prong 30, abutting the riser 31 and the other end abutting the interior of the head tending to 105

press the same toward the front of the fastener, its action being limited by contact of the neck 27 with the front end of the opening 29.

5 The forward end of the plate 24 contains a recess 33 the inner edge of which is pressed by the spring past the corresponding edge of an opening 34 in the plate 12, there being a registering opening 35 in the plate 14.

10 The keeper, shown in Figs. 4, 5 and 6 consists of a sheet of metal bent along its median line to produce outer and inner elements respectively 40 and 41, the entire margin of these elements being depressed as at 15 42 and 43.

The front or outer plate is sheared triangularly as at 44 to produce sharp spurs 45 adapted to pierce the material 11, strike upon the inner surface of the mating member 20 41 and by it be deflected and clinched in the material causing it to fill the bight of the loop 46 produced by bending the plate and becoming securely attached therein.

A flat post 47 is rigidly fixed centrally of 25 the front element 40 to extend outwardly at a right angle, the outer end of the post being curved or bevelled and its front edge provided with a recess or catch 48.

In operation, the parts being attached in 30 the manner described the flap 11 is brought over the element 10 in such manner that the post 47 is caused to enter the opening 34.

Upon the application of suitable pressure 35 the curved end of the post when in contact with the edge of the recess 33, moves the plate 24 and head 28 rearwardly opposing the spring 32, until the recess 48 permits the plate to move forward engaging in the recess and thus positively locking the parts 40 together, the end of the post at that time being entered in the opening 35.

To release the keeper it is merely necessary to retract the head 28 to its limit, thereupon freeing the plate 24 from the recess 48 in the post and separating the parts in the usual manner.

Thus the entire fastener mechanism consists of only three pieces, a spring and a substantially integral keeper, the construction 50 of which is essentially simple.

As changes of construction could be made within the scope of the invention, it is intended that all matter contained in the foregoing description or shown in the accompanying drawings shall be interpreted as illustrative and not in a limiting sense.

Having thus described my invention, what I claim as new and desire to secure by Letters Patent, is:—

60 1. A bag fastener comprising a pair of spaced plates, respectively inner and outer rigidly interengaged at their oppositely flanged edges and containing registering openings, a keeper having an element enterable in the mentioned openings, said element

being recessed, a slide movable in the space between said plates, said slide having a part engageable in the recess of said keeper element, a hollow circular head formed on said slide, said head extending through the outer plate into position for operation, and means in said head adapted to normally move said slide into engaging position with said keeper.

2. A bag fastener comprising upper and lower plate members spaced apart and containing registering openings, flanges formed with each member to cause rigid interengagement, a slide movable between said plate members, means for guiding and means for limiting the movement of said slide formed on said lower member, said slide normally projecting partially into the space between the mentioned openings, a head formed on said slide, said head extending accessibly through an opening in the upper of said plate members, and means for resiliently pressing said slide into engaging position.

3. A bag fastener comprising a casing, a plate spaced parallel therewithin, said casing and plate having registering openings, co-operating means formed on said casing and plate for securing the plate in rigid relation, a detent slide movable in the space between said casing and plate, guides integral with said plate for said slide, an upturned neck on said slide operable in an opening in said casing top, a hollow head on said neck normally covering the opening, a prong on said casing disposed within said head, a spring held by said prong adapted to press said head forward causing the detent slide to partially intercept the openings in said casing and plate, and a member enterable in the openings engageable by said slide.

4. A bag fastener comprising an escutcheon plate having downturned flanged side and end walls said plate having a post receiving opening, a second plate having upturned side walls interjacent the side walls of the escutcheon plate and having an opening registering with the opening in said escutcheon plate, elongated end members on said second plate having flanged ends intermediate their length engaging the end walls of said escutcheon plate, lugs formed on the end walls of the escutcheon plate to fold over said flanged ends, extensions on said elongated member engageable with the bag material, a slide operable in the space between said plates, said slide having an attenuated portion extending through an opening in said escutcheon plate, a hollow circular head formed on said attenuated portion movable over the escutcheon plate, and means in said head for advancing said slide to engage a keeper entered in the mentioned openings.

5. In a bag fastener, the combination with a casing, a slide movable therein and means for actuating said slide, said means extending over the casing, said casing having an opening partially intercepted by the slide, of a keeper composed of a single plate bent to produce two equal leaves, a pair of inwardly extending spurs formed by shearing one of said leaves, said spurs being adapted 10 to pierce material entered between the leaves shaped to bend towards the fold in said

plate and become clinched against the opposite leaf, and a recessed post fixed in the first named leaf adapted to enter the opening in said casing to be engaged by said slide. 15

This specification signed and witnessed this fourth day of December, 1922.
